UNITED STATES PATENT OFFICE.

WILLARD TALBOTT, OF SPOKANE, WASHINGTON.

RAIL-FASTENING.

1,178,763.

Specification of Letters Patent. Patented Apr. 11, 1916.

Application filed February 1, 1916. Serial No. 75,537.

To all whom it may concern:

Be it known that I, WILLARD TALBOTT, a citizen of the United States, residing at Spokane, in the county of Spokane and State 5 of Washington, have invented a new and useful Rail-Fastening, of which the following is a specification.

The device forming the subject matter of this application is a rail fastening, and the 10 present invention aims to combine, in a novel manner, with a railroad rail and with a tie, a screw of novel form, the ends in view being so to arrange the parts that the upward 15 pull of the rail will have a minimum effect on the screw so far as lifting the screw is concerned, so to assemble the screw with the tie and with respect to the rail that the horizontal thrust of the rail will have no vertical component tending to lift the screw; 20 to cause the head of the screw to coat with the tie in such a manner that an efficient brace against the horizontal thrust of the rail will be afforded; to provide novel means whereby water will be prevented from entering the screw hole: so to fashion the 25 threads of the screw and to position the screw with respect to the rail and the tie that a maximum hold for the screw on the tie will be afforded: and, generally, to improve and to enhance the utility of devices of the sort shown in this application.

With the above and other objects in view which will appear as the description proceeds, the invention resides in the combination and arrangement of parts and in the details of construction hereinafter described and claimed, it being understood that changes in the precise embodiment of the invention herein disclosed can be made without 35 in the scope of what is claimed, without departing from the spirit of the invention.

In the accompanying drawing:—Figure 1 shows in top plan, a railroad rail assembled with a portion of a tie, through the instrumentality of the screw forming a part of this application; Fig. 2 is a vertical cross section of the structure shown in Fig. 1; Fig. 3 is a side elevation of the screw.

In the accompanying drawings, the number 50 1 designates generally a tie ordinarily fashioned from wood. There appears in the drawings, a railroad rail 2 comprising a ball 3, a web 4, and a flange 5, the flange 5 resting on the upper surface of the tie 1.

In carrying out the present invention

there is provided a screw 6 including a hexagonal head 7, a conical neck 8 and a shank 9, the shank 9 being provided adjacent its lower end with threads 10 and terminating at its lower end in a point 11. The lower 60 face 12 of the threads 10 are so disposed with respect to the upper faces 14 of the threads as to define a right angle.

The invention contemplates, preferably, the use of two screws disposed upon opposite sides of the rail 1 but to simplify the description, the same will be confined to one screw.

The shank 9 of the screw 6 is threaded into the tie 1 at an acute angle to the vertical, and extends beneath the flange 5 of the rail as clearly shown in Fig. 2, thereby to increase the efficiency of the screw as a means for resisting the upward pull of the rail. The conical neck 8 is firmly wedged 75 into the tie 1 to act as a stop-water for the screw-hole. The head 7 engages the upper surface of the flange 5 for the obvious purpose of holding the rail down on the tie. The inner edge of the neck 8 is in contact 80 with the edge of the flange 5 of the rail and is vertically disposed, whereby the horizontal thrust of the rail will have no vertical component tending to lift the screw. The outer edge of the head 7 engages the tie 1 to 85 serve as a brace against the horizontal thrust of the rail. Owing to the fact that the upper and lower faces 14—12 of the threads 10 of the screw define a ninety degree angle, the hold of the screw on the tie 1 is enhanced, notably when the inclined position 90 of the screw is noted.

Having thus described the invention, what is claimed is:—

In a fastening for railroad rails, a tie; a 95 rail comprising a flange resting on the tie; and a screw embodying a head, a conical neck and a shank; the shank being inserted into the tie at an acute angle to the vertical and extending beneath the flange thereby to 100 increase the efficiency of the screw as a means for resisting the upward pull of the rail, the neck being firmly wedged into the tie to act as a stop-water for the screw hole, the head overlapping the upper surface of the 105 flange, the inner edge of the neck being in contact with the edge of the flange and being vertically disposed whereby the horizontal thrust of the rail will have no vertical component tending to lift the screw, the 110

outer edge of the head engaging the tie to serve as a brace against the horizontal thrust of the rail and the screw having threads the upper and lower surfaces of which define a ninety degree angle whereby the hold of the screw on the tie will be increased.

In testimony that I claim the foregoing as

my own, I have hereto affixed my signature in the presence of two witnesses.

WILLARD TALBOTT.
